Atty's.

UNITED STATES PATENT OFFICE.

ANSEL F. GURNEY, OF NATICK, MASSACHUSETTS.

ELECTRICAL CONNECTION.

1,286,592.

Specification of Letters Patent. Patented Dec. 3, 1918.

Application filed January 21, 1918. Serial No. 213,018.

To all whom it may concern:

Be it known that I, ANSEL F. GURNEY, a citizen of the United States, and a resident of Natick, county of Middlesex, and State of Massachusetts, have invented an Improvement in Electrical Connections, of which the following description, in connection with the accompanying drawings, is a specification, like characters on the drawings representing like parts.

This invention pertains to improvements in electrical connections, and more particularly, though not exclusively, to connections for use with a protective flexible armored cable commonly used for protecting electric wire in automobiles and the like. While my invention is of general application, I have elected to show it as applied to a single wire system.

In the drawings, which show a preferred form of one embodiment of my invention:

Figure 1 is a plan view, showing a preferred form of connector applied to an electric automobile lamp;

Fig. 2 is an enlarged section on the line 2—2 of Fig. 1; and

Fig. 3 is a transverse section on the line 3—3 of Fig. 2.

The preferred form of my invention comprises an armored cable 4 having an expanded portion 5 at one end thereof adapted to rest against a shoulder 6 of an interiorly threaded sleeve 7, the threads of which engage the threaded portion of a male terminal plug 8, the end of which preferably bottoms against the expanded end 5 of the cable. The terminal plug 8 is preferably split, as shown, to receive interiorly a conductive terminal means into which the wire passing through the flexible tubing 4 may be secured by any suitable means, though preferably by soldering. To hold the conductive terminal means 10 against longitudinal movement relative to the terminal plug 8, I have shown a groove 11 in the conductive terminal means and a coöperating pin 12 in the non-conductive terminal plug 8. To secure the terminal plug 10 of the lamp to the female connecting element 12', I preferably provide projecting pins or dowels 13 adapted to enter into a slot 14 in the female connector element, thereby providing a bayonet joint connection.

While I have shown and described a preferred form of one embodiment of my invention, it will be understood that major changes involving omission, substitution, alteration and reversal of parts, and even changes in the mode of operation, may be made without departing from the scope of my invention, which is best defined in the following claims:

1. A connector comprising, in combination, a sleeve providing a shoulder, an armored cable having an expanded end for engagement with said shoulder and a terminal plug of non-conductive material entered in said sleeve and pressing against the flanged end of said armored cable.

2. A connector comprising, in combination, a sleeve for engagement with the end of an armored cable and a split terminal plug entered in said sleeve, said plug having threads at one end extending across the split therein and engaging threads on the interior of said sleeve.

3. A connector comprising, in combination, a sleeve for engagement with the end of an armored cable and a split terminal plug entered in said sleeve and threaded thereto.

4. A connector comprising, in combination, a sleeve, a split terminal plug of non-conductive material, and a conductive terminal in said split terminal plug removable therefrom when said terminal plug is removed from said sleeve.

5. A connector comprising, in combination, a sleeve, a split terminal plug of non-conductive material, a conductive terminal in said split terminal plug removable therefrom when said terminal plug is removed from said sleeve, and means opposing longitudinal movement of said conductive terminal in said non-conductive terminal plug.

6. A connector comprising, in combination, a terminal plug of non-conductive material, split longitudinally and provided with a threaded portion; and a coöperating sleeve interiorly threaded for engagement with the threaded portion of said terminal plug and effective for holding together the split portions of said terminal plug.

7. A connector comprising, in combination, a terminal plug of non-conductive material, split longitudinally and provided

with a threaded portion; an armored cable having an expanded end, and a coöperating sleeve interiorly threaded for engagement with the threaded portion of said terminal plug and effective for holding together the split portions of said terminal plug while said terminal plug and sleeve engage be-

tween them the expanding portion of said armored cable to maintain the same in operative relation thereto.

In testimony whereof, I have signed my name to this specification.

ANSEL F. GURNEY.
